UNITED STATES PATENT OFFICE.

CHARLES GOODYER AND WILLIAM MORSE, OF WARREN, PENNSYLVANIA.

CLOTHES-DRIER.

SPECIFICATION forming part of Letters Patent No. 334,656, dated January 19, 1886.

Application filed February 24, 1885. Serial No. 156,717. (Model.)

To all whom it may concern:

Be it known that we, CHARLES GOODYER and WILLIAM MORSE, of Warren, Warren county, Pennsylvania, have invented a new and Improved Clothes-Bar, of which the following is a full, clear, and exact description.

The object of our invention is to provide a new and improved clothes-bar which is simple in construction, and which can be folded very compactly when not in use.

The invention consists in the combination, with a hollow upright having offsets in the sides, the said offsets having openings, of a slide in the upright, and of arms or bars pivoted to the side edges of the slide and projecting through the said openings.

Reference is to be had to the accompanying drawings, forming part of this specification, in which similar letters of reference indicate corresponding parts in all the figures.

Figure 1 is a front elevation of our improved clothes-bar, the same being erected for use, and parts being broken out. Fig. 2 is a sectional plan view of the same. Fig. 3 is a sectional plan view of the upright.

The upright is formed of a post, A, and a back, B, each provided with vertical groove C in its inner surface. The back B is provided with flanges D, forming the side edges of the upright, and the front and back are united by screws or bolts. The upright is provided with legs E or any other suitable base. On the side of the upright is a series of offsets, F, which have horizontal tops G, and downwardly-inwardly inclined sides H. A slot is formed in the top of each offset. A sliding piece, J, is located in the vertical groove C, and is provided with a button, K, projecting through a vertical slot, I, in the front. In

each edge of the sliding piece J as many bars 40 or arms L are pivoted as there are offsets F, each bar or arm being pivoted in a recess, M, in the edge of the piece J, the bottoms of which recesses are horizontal, and the backs inclined from the inner ends of the bottoms upward or 41 outward. A slot, N, is formed in the bottom of the inclined part of each offset F.

The operation is as follows: To fold the clothes-bar, the button K is moved downward and the slide J is moved downward, and thereby the arms L are swung upward and against the sides of the upright, into the position shown in dotted lines, and the arms L resting against the inner surfaces of the inclined sides of the offsets F. To adjust the clothes-bar for use, 55 the button K is pushed, and thereby the slide J is moved upward and the bars or arms L are swung downward into a horizontal position, as shown in Fig. 1, the bottom edges of the arms L resting on the upper ends of the inclined sides of the offsets H.

Having thus described our invention, we claim as new and desire to secure by Letters Patent—

In a clothes-bar, the combination, with an 65 upright having the offsets F, and the sides H, inclined from the outer ends of the offsets down toward the vertical central line of the upright, of a slide, J, between the uprights, which slide has beveled recesses in the side edges, and bars 70 pivoted in the said recesses and passed through openings in the offsets, substantially as here-in shown and described.

CHARLES GOODYER.
WILLIAM MORSE.
